CUP AND SAUCER STAND

Seymour Postal, Spring Valley, N. Y.

Application July 2, 1952, Serial No. 20,444

Term of patent 3½ years

(Cl. D80—10)

To all whom it may concern:

Be it known that I, Seymour Postal, a citizen of United States of America, residing at Spring Valley, in the county of Rockland and State of New York, have invented a new, original, and ornamental Design for a Cup and Saucer Stand, of which the following is a specification, reference being had to the accompanying drawing, forming part thereof.

In the drawing:

Fig. 1 is a front perspective view of a cup and saucer stand showing my new design;

Fig. 2 is a top plan view.

I claim:

The ornamental design for a cup and saucer stand, substantially as shown.
